UNITED STATES PATENT OFFICE.

HENRY D. GROSS, OF KENNETT, MISSOURI.

FURNACE STOKER.

Application filed October 4, 1920. Serial No. 414,565.

To all whom it may concern:

Be it known that I, HENRY D. GROSS, a citizen of the United States, residing at Kennett, in the county of Dunklin and State 5 of Missouri, have invented certain new and useful Improvements in Furnace Stokers; and I do hereby declare the following to be a full, clear, and exact description of the invention, such as will enable others skilled 10 in the art to which it appertains to make and use the same.

The object is to provide a simple and efficient stoking apparatus for use in connection with furnaces, whereby cotton seed 15 hulls, shavings from planing machines, saw-dust and the like, powdered or granular forms of fuel of a relatively light character may be economically fed to furnaces as a substitute for the forms of fuel now in common 20 use, to the end that these otherwise waste materials may be utilized to advantage to effect an economy in the use of standard forms of fuels and avoid the necessity of separately destroying such waste materials 25 at an additional expense; and with these objects in view, the invention consists in a construction and combination of parts of which a preferred embodiment is shown in the accompanying drawings, wherein

Figure 1 is a side view of a stoking apparatus embodying the invention applied in the operative position to a furnace,

Figure 2 is a plan view of the same,

Figure 3 is a longitudinal sectional view 35 thereof showing in dotted lines the adjusted or choking position of the trap,

Figure 4 is an end view looking at the discharge or furnace end of the chute to show the construction of the yielding damper,

Figure 5 is a detail longitudinal section 40 of the discharge end of the chute showing in full and dotted lines different adjusted positions of the damper which can be regulated to suit the furnace draft and the freedom 45 with which the fuel material flows through the chute.

The stoker consists essentially of a chute 10 of which the receiving end is adapted to be arranged under the discharge spout of a 50 conveyor or blower by which the cotton seed hulls or other material is deposited, the opposite or discharge end of the chute being extended through an opening 11 in the furnace wall 12 so as to discharge into the fire 55 box or combustion chamber of the furnace, a cap 12' being extended over the portion of

the chute which extends through the wall so as to support the masonry or brick work spanning the same.

Immediately outside of the plane of the 60 furnace wall there is arranged a slide or gate 14 by which the passage through the chute may be regulated and by which it may be completely cut off when the stoker is not in use. The side edges of the slide or 65 gate, in the construction illustrated are fitted in guides 15 on the side walls of the chute.

Extending downwardly and forwardly from the plane of the slide or gate and toward the discharge end of the chute, is a 70 yielding damper 16, pivotally mounted as at 17 and adapted to bear at its free end upon the bottom of the chute, the cotton hulls or other fuel such as shavings, saw-dust and the like being adapted to pass 75 under the edge of said damper subject to the action of gravity tending to feed the fuel toward the furnace and the internal draft of the furnace which tends to suck or draw the fuel into the fire box or combustion chamber. The sensitiveness of the damper to the 80 gravitational action of the fuel and the suction in the fire box may be regulated by varying the length of the damper, to which end the latter is provided with an adjustable extension 18 slotted as at 19 and engaged by a bolt 20 or similar fastening means, it being obvious that when the damper is extended, it will ride more easily upon the material flowing beneath the same and will tend to 85 feed the material more freely, whereas when reduced in length by the rearward adjustment of the extension member, it will occupy a more nearly vertical position and will yield less readily both to the action of gravity on the fuel and the draft within the furnace.

At the receiving or inlet end of the chute there is arranged a tilting trap 21 fulcrumed as at 22 and adapted to be reversely tilted 100 to direct the fuel such as cotton hulls, shavings, saw-dust and the like in the opposite direction for discharge upon the ground or into a suitable receptacle, when the rapidity with which the fuel material is fed to the 105 chute is greater than should be supplied to the furnace. In other words, if the fuel is being deposited in the trap more rapidly than it should be fed to the furnace, the trap may be tilted in the opposite direction at intervals to diverge certain portions or a certain percentage of the material while the 110

2
balance is permitted to find its way along the chute to be fed under the damper to the fire box or combustion chamber. The tilting trap constitutes a convenient means whereby the operator may regulate the rapidity with which the fuel is fed along the chute.

It will be understood that the above device constitutes a means whereby an ordinarily waste product which under the present practice is usually destroyed and the destruction of which involves an additional expense in connection with the business in which the material is a waste product. By providing for utilizing such material as the fuel for a boiler furnace or the like, other forms of fuel may be saved or used in smaller quantities, and by regulating the rapidity with which this waste material is supplied as a fuel to the furnace, the draft arrangements of the latter may be readily controlled and a uniform heat maintained without the constant attention of a fireman as required in the use of the ordinary forms of fuel.

25. What I claim is:—

A furnace stoking apparatus comprising a chute adapted to have its discharge end in communication with a furnace fire box,

a yielding feed regulating damper disposed in a forwardly and downwardly inclined relation to the path of travel of the fuel and pivotally mounted in a plane above the bottom of the chute, an adjustable extension carried by said damper whereby the angle of inclination of the damper may be varied and thereby vary the retarding action of the damper; a second damper arranged to intercept and regulate the passage of fuel to the inclined damper; the receiving end of the chute having its bottom cut away, a reversible trap pivoted to the side walls of the chute adjacent the cut away portion and adapted to be moved into a position at an angle to the chute to prevent fuel being deposited in the chute when the trap is in one position and thereby prevent overstocking of the furnace, and said trap adapted to form a part of and an extension for the chute when the trap is in its normal position.

In testimony whereof I affix my signature in presence of two witnesses.

HENRY D. GROSS.
